(57) **CLAIM**

We claim the ornamental design for a hockey stick, as shown and described.

DESCRIPTION

FIG. 1 is a tridimensional view of a hockey stick in accordance with a first embodiment of our new design.

FIG. 2 is a front elevational view of the design of FIG. 1.
FIG. 3 is a first side elevational view of the design of FIG. 1.

FIG. 4 is a second side elevational view of the design of FIG. 1, opposite the first side.

FIG. 5 is a rear elevational view of the design of FIG. 1.
FIG. 6 is a top plan view of the design of FIG. 1.

FIG. 7 is a bottom plan view of the design of FIG. 1.

FIG. 8 is a detailed tridimensional view of the blade of the hockey stick of FIG. 1, taken from region 8-8 of FIG. 1.

FIG. 9 is a detailed front elevational view of the blade of the hockey stick of FIG. 1, taken from region 9-9 of FIG. 2.

FIG. 10 is a tridimensional view of a hockey stick in accordance with a second embodiment of our new design.
FIG. 11 is a front elevational view of the design of FIG. 10, the first side elevational view, second side elevational view, rear elevational view, top plan view and bottom plan view corresponding to that of the first embodiment as shown in FIGS. 3 to 7, respectively.

FIG. 12 is a detailed tridimensional view of the blade of the hockey stick of FIG. 10, taken from region 12-12 of FIG. 10; and,

FIG. 13 is a detailed front elevational view of the blade of the hockey stick of FIG. 10, taken from region 13-13 of FIG. 11.

The broken lines do not form part of the claimed design.
